Primary Examiner — T Chase Nelson(74) *Attorney, Agent, or Firm* — Thompson Coburn LLP**(57) CLAIM**

The ornamental design for a shoe sole, as shown and described.

DESCRIPTION

FIG. 1 is a heel-end perspective view of a shoe sole showing our new design;

FIG. 2 is a toe-end perspective view thereof; and,

FIG. 3 is a bottom plan view thereof.

The broken lines immediately adjacent the shaded areas represent the bounds of the claimed design while all other broken lines are directed to environment; the broken lines form no part of the claimed design.

1 Claim, 3 Drawing Sheets# US D832,564 S
